UNITED STATES PATENT OFFICE.

RICHARD EDWIN WEEDON, OF WASHINGTON, DISTRICT OF COLUMBIA.

SWITCH-POINT PROTECTOR.

Application filed April 2, 1926. Serial No. 99,300.

The invention relates to railway switches and more particularly to protective means therefor, whereby the life of the switch point is materially prolonged and the shape 5 preserved, which is essential to safety and the proper working of the switch.

A further purpose of the invention is to mount the protector on the switch point, thereby preventing the weakening of the 10 track rail and insuring the same being unobstructed when the adjacent switch point is moved away therefrom, as when closing the switch to the opposite track rail.

While the drawings illustrate a preferred 15 embodiment of the invention it is to be understood that in adapting the means to meet specific needs and requirements, the design may be varied and such other changes in the minor details of construction may be re- 20 sorted to within the scope of the invention as claimed, without departing from the spirit thereof.

For a full understanding of the invention and the merits thereof, reference is to be had 25 to the following description and the drawings hereto attached, in which—

Figure 1 is a fragmentary side view of a 30 switch point and track rail provided with protective means for the switch point embodying the invention.

Figure 2 is an end view of the protector, showing it associated with a track rail, which is indicated in section, and

Figure 3 is a top plan view of the parts 35 illustrated in Figure 1, a portion of the head of the track rail being broken away.

Corresponding and like parts are referred to in the following description and designated in the several views of the drawings 40 by like reference characters.

The numeral 1 designates a track rail and 45 2 a switch point of ordinary construction, illustrated to demonstrate the application of the invention.

An arm 3 is secured at one end to the switch point 2 in any substantial and preferred way and projects from said point in line therewith, the projecting end being reduced to receive the protector and having 50 the terminal portion threaded to receive a nut 4 which serves as means to retain the

protector upon the projecting end of the arm. As indicated, the arm 3 is secured to the switch point 2 by means of rivets 5, however, it is to be understood that the arm may 55 be attached to the switch point in any determinate way.

The protector comprises a tubular body 6 and oppositely disposed wings 7 which are of similar formation to admit of either of 60 the wings occupying an operative position. The protector is preferably made of manganese steel, so as to resist wear. The opening of the tubular body 6 is of non-circular outline and obtains a snug fit upon the outer 65 reduced portion of the arm 3 and is thus prevented from turning thereon. The wings 7 are disposed approximately at diagonally opposite points of the tubular body, as indicated most clearly in Figure 2, 70 and one side of each is flat and the opposite side transversely and longitudinally curved, as indicated most clearly in Figures 2 and 3. The flat side of the wings is disposed to lie 75 against the side of the head of the track rail 1 and the transversely and longitudinally curved side is adapted to face outwardly, or away from the head of the track rail, to offer little or no resistance to the contact 80 of the wheel flange therewith, when engaging and riding over the protector. When one of the wings of the protector becomes worn or otherwise unfitted for effective service, the protector is removed from the arm 85 3 and reversed to bring the opposite wing in active position.

By mounting the protector upon the switch point it moves therewith and is held away from the track rail when the adjacent switch point is moved laterally therefrom, 90 and in consequence, the track rail is unobstructed and is not weakened, as would be the case if the protector were attached directly thereto. The end of the arm 3 attached to the switch point is flattened and 95 disposed against that side of the switch point facing the track rail and, as a result, a portion of the arm and a portion of the tubular body 6 extends into the space formed 100 between the head and foot of the rail when the switch point is closed thereagainst, as indicated most clearly in Figures 2 and 3.

It is also observed that the protector may be attached to the switch point in the field and at a minimum expense.

Having thus described the invention, I claim:

1. In a railway switch, a protector reversibly mounted upon and carried by the switch point.
2. In a railway switch, a protector mounted upon and carried by the switch point, said protector consisting of a tubular body and an offstanding wing, one side of the wing being flat and the opposite side curving transversely and longitudinally.
3. A reversible switch point protector adapted to be mounted upon and carried by the switch point, the same comprising a tubular body and oppositely disposed wings, one side of the wings being flat and the opposite side curving transversely and longitudinally.
4. In a railway switch and in combination with the switch point, an arm projecting longitudinally from the extremity of the switch point and a protector detachably and

reversibly mounted upon the projecting end of the arm and comprising a tubular body and oppositely disposed wings which have the sides facing outwardly from the track rail transversely and longitudinally curved. 30

5. In a railway switch, and in combination with the switch point, an arm attached at one end to the switch point and having its opposite end projecting and of non-circular outline in cross section and having its terminal portion threaded, a protector mounted upon the projecting end of said arm and comprising a tubular body and oppositely disposed wings, one side of the wings being flat and the opposite side being transversely and longitudinally curved, the opening of the tubular body snugly fitting the projecting end of the arm and held from turning thereon, and a nut fitted to the threaded terminal of the arm to retain the protector in place thereon. 40

In testimony whereof I affix my signature.

RICHARD EDWIN WEEDON. [L. S.]
